LOADING APPARATUS

Roy S. Bigelow, Chicago, Ill., assignor to Goodman Manufacturing Company, Chicago, Ill., a corporation of Illinois

Application April 5, 1939, Serial No. 266,054

2 Claims. (Cl. 198—220)

This invention relates to improvements in loading apparatus, and more particularly relates to a new and improved mobile loading apparatus of the shaker conveyer type particularly adapted to load material onto a face conveyer in mines of low head room.

Heretofore, shaker conveyors having extensible shovels on the forward end thereof have been extensively used for loading coal in narrow working places in mines of low head room. These conveyers have had certain advantages over other types of loading apparatus, which are chiefly due to their low overall height, low initial cost, simplicity in construction and operation, and ease with which the shovel can be extended into the coal to positively pick it up. Due, however, to the fact that props holding up the roof limit the range of swinging movement of the shovel, and the fact that the entire conveyer is too bulky to be moved along the working place as the loading operation progresses, such a loading apparatus has not been satisfactory for operation along a long face.

The principal objects of my invention are to provide a novel, mobile conveyer of the shaker type particularly adapted for operation along long faces in coal of low head room, for loading into a face conveyer extending parallel to the working place.

Another object of my invention is to provide such an apparatus which is of a low, compact, and unitary mobile construction, so arranged that the entire apparatus may be moved along the ground by power, and the extensible trough section and shovel may be extended and swung by power to pick up material from various places along the working face.

Other objects of my invention will appear from time to time as the following specification proceeds and with reference to the accompanying drawings wherein:

Figure 1 is a view in side elevation of an apparatus constructed in accordance with my invention shown in working position in a mine room, with certain parts of the conveyer drive mechanism broken away and shown in transverse section;

Figure 2 is a diagrammatic plan view of the apparatus positioned in a mine room, for loading onto a conveyer extending parallel to the working face;

Figure 3 is an enlarged plan view of the apparatus, with certain parts shown in horizontal section;

Figure 4 is an enlarged sectional view of the

apparatus taken substantially along line 4—4 of Figure 3; and

Figure 5 is an enlarged detail view of one of the winding drums, with certain parts broken away and certain other parts shown in horizontal section.

Referring now in particular to the drawings, the embodiment of my invention illustrated includes generally a base 10, which forms the lower part of a housing for a reciprocable drive mechanism 11, which is adapted to reciprocably drive a shaker pick-up conveyer 12, herein shown as including a trough section 13 mounted on and driven from a reciprocably driven support means 14, in such a manner as to cause material to move therealong (see Figure 4). Said base is mounted on the ground and may be slidably moved therealong on its bottom to advance the entire apparatus along the working place.

The pick-up conveyer 12 includes an extensible trough section 15, having a shovel 16 on its forward end, which is adapted to be slidably supported on the ground. Said extensible trough section and shovel are operatively connected with the trough section 13 by means of a feeder head 17, generally indicated by reference character 17, a reciprocating trough section 18, and a swivel 19, which permits swinging movement of said extensible trough section in a horizontal plane, to position the shovel to pick up material from various points along the mine face.

The swivel 19 may be of any type well known to those skilled in the art and includes a relatively short trough section having a widened and rounded forward end 20 with outwardly flared rounded sides. This trough section is connected to the forward end of the trough section 13 at its rear end and its widened forward end 20 has the widened rear end of a trough section 21 nested therein and pivotally connected thereto. As shown in Figure 1, the trough section 21 is mounted on a shoe 22 at its forward end, and also has the reciprocating trough section 18 detachably secured to its forward end by means of the usual connecting bolts.

The feeder head 17 may be of an automatic type, similar to that shown in the Bergmann Patent No. 2,154,060, and is no portion of my present invention so will only herein be described in sufficient detail to render my present invention clearly understandable. Said feeder head includes a bracket 23 mounted on the forward end of the reciprocating trough section 18 and extending upwardly along opposite sides thereof. A plurality of rollers 24, 24 are mounted on oppo-

site sides of said bracket and form a means for supporting said reciprocating trough section on flanged bearing members 25, 25 which project laterally from opposite sides of the extensible trough section 15 (see Figures 1 and 3). Said extensible trough section is supported above the ground at its rear end on a shoe 27 and said bracket and rollers thus form a support for the forward end of said reciprocating trough section. Friction grip blocks 28, 28, connected with the bracket 23, are provided to grip the projecting bearing plates 25, 25 upon certain strokes of the conveyer, to extend or retract said extensible trough section, as desired, in a well known manner which is clearly shown and described in the aforementioned Bergmann patent, so will not herein be described in detail.

The conveyer drive mechanism, as herein shown, is of a type having a low overall height and is similar to that shown in Patent No. 1,908,087, which issued to R. A. Walter on May 9, 1933, so will not herein be described in detail. Said drive mechanism includes a motor 20 mounted on the base 10 on a bracket 30 and driving a bevel gear 31 through a bevel motor pinion 33. Said bevel gear is mounted on and drives a vertical shaft 34. A pinion 35 is likewise mounted on said shaft and meshes with and drives a spur gear 36 on a vertical shaft 30 which is mounted on and depends from a cover 37 for said base and housing. Another spur gear 40, similar to the spur gear 36, is mounted on the cover 37 on a vertical shaft 41, depending from said cover. Said last mentioned spur gear 35 is driven from the spur gear 36 by means of a spur gear 43. A crank pin 44 is mounted on and depends from each spur gear 36 and 40. Each of said crank pins has a slide 45 mounted on the lower end thereof which is slidably mounted in a slot 46 in a bar 47. Said bar is pivotally mounted at its center on a vertical shaft 49, which is pivotally mounted at its lower end in a cross head 50, slidably mounted in a guide 51, extending along the bottom of the housing and base 10.

45 The cross head 50, as herein shown, has the upwardly projecting support member 14 formed integrally therewith, which extends through a slot 54 formed in a cover member 55, covering a central opening in the cover 37.

50 Referring now to the means for swinging the extensible trough section 15 about the axis of the swivel 19, a pair of winding drums 59, 59 is provided. Said winding drums are each mounted on the top of the cover 37 and are each encased in a housing member 60 bolted on the top of said cover. Each of said winding drums is of a similar construction and is driven from the shaker conveyer drive mechanism 11 in a similar manner, so the same part numbers will be applied to each of said drums, and one only will herein be described in detail. The housing 60 forms a bearing support for the upper end of a vertical shaft 61, which shaft has a winding drum 59 journaled thereon and forms a drive member therefor (see Figure 4). The lower end of the vertical shaft 61 extends within the housing for the conveyer drive mechanism through the cover 37, which cover forms a bearing support for the lower portion of said shaft. A spur gear 63 is mounted on the lower end of said shaft and meshes with and is driven from a spur gear 64 on the vertical shaft 61.

A suitable clutch, such as, a jaw clutch 65, is provided to selectively connect the drum 59 with the vertical shaft 61 through a spur gear 66, free-

ly mounted on said shaft just above the winding drum 59. Said spur gear meshes with and drives a spur pinion 67 mounted on a vertical stud 68 mounted on and projecting upwardly from an upper flange 69 of said winding drum. Said pinion meshes with an internal gear 70 formed integral with a flange 71 projecting upwardly from the upper flange 69 of said winding drum, adjacent the outer periphery thereof (see Figures 4 and 5). 5 10

A suitable braking means is provided to hold each winding drum from rotation, to permit said respective drum and the cable thereon to serve as a retarding member, and to prevent the idle drum from unwinding too fast and causing an excess amount of slack to form on its associated cable. Said braking means, as herein shown, includes a friction band 72 adapted to engage the outer periphery of the flange 71. Said band may be held in engagement with said flange by means of a rod 73 which has a head 74 abutting a lug 75 projecting from one end of said friction band. Said rod extends through said lug and through a lug 76 projecting from the opposite end of said friction band and projecting through the housing 60. A projection 77 from said friction band, engaging a notched portion of said housing, is provided to hold the end of the friction band adjacent the lug 76 from movement. A hand wheel 78 is threaded in the outer end of the rod 73 so that rotation thereof in one direction will cause said friction band to tighten on the flange 71, and rotation of said hand wheel in an opposite direction will permit said friction band to be released from said flange.

Each winding drum 59 has a flexible cable 79 wound thereon. Said cables are adapted to be attached to fixed abutments (not shown), for moving the entire apparatus along the ground. Said cables are also adapted to be connected to opposite sides of the trough line for swinging the shovel 16 about the axis of the swivel 19. As herein shown, the cable 79 on the winding drum 59, which is the left hand winding drum when looking towards the shovel 16, may extend around a sheave 80 on the base 10 and around a sheave 81 mounted on a bracket 82 spaced forwardly and laterally from said base. Said bracket may be held in position by means of a jack 83 adapted to be secured between the mine roof and floor. The free end of said cable 50 may be detachably connected to one side of the bracket 23, on a lug 84, projecting laterally therefrom. The opposite flexible cable 79 extends around a sheave 85 on the base 10, around another sheave 86 mounted in a bracket 87 and 55 adapted to be held in position by a jack 88. Said cable may be attached at its free end to a lug 89, projecting laterally from the side of the bracket 23 opposite from the lug 84. The application of power to one winding drum or the other will 60 thus swing the extensible trough section about the axis of the swivel 19 to position the shovel 16 to gather material from various points along the working face without changing the position of the base 10. It should be understood that 65 when both cables are connected to the extensible trough section, for swinging said trough section, that a slight amount of tension is maintained on the cable connected to the idling drum by its friction band 72, to prevent the formation of 70 an excess amount of slack on said cable. It should likewise be understood that either one or both of the cables 79 may be used to move the base and drive mechanism along the mine bottom, and that said mechanism may be manipu- 75

lated or turned by using one cable as a draft device and the other cable as a retarding device, using either of the friction bands 72, to hold the respective winding drum 59 from rotation.

5 Referring now in particular to Figures 1 and 2 and the use and operation of the device of my invention, the apparatus is usually started at one corner of the room. During the loading operation, the base 10 may be held in position by 10 means of a plurality of jacks 90, 90 adapted to be interposed between said base and the mine roof. The discharge end of the trough section 13 may overhang a conveyer 91 extending parallel to the working place. Said conveyer may be of 15 any type but is herein preferably shown as being of the well known belt type adapted to discharge into another conveyer 93 which may transport material out from the working place to the entry. As one section of the working place is completely 20 loaded out onto the belt conveyer 91 by extension or retraction of the shovel 16 as it is reciprocably driven by the conveyer drive mechanism and is moved back and forth across the face by the cables 79, 79, the entire apparatus is moved along 25 the working place by means of either one or both of the cables 79 to a new location until the entire coal face has been loaded onto the belt conveyer 91. The working place may be undercut again, and the undercut coal shot down and 30 the loading operation be repeated, the apparatus then advancing across the face in an opposite direction.

While I have herein shown and described one form in which my invention may be embodied, it 35 will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a material loading apparatus, a shaker conveyer drive mechanism adapted to be slidably 40 moved along the ground on its bottom and including a housing, the bottom of which forms a base for said apparatus, a conveyer trough section reciprocably mounted on said drive mechanism and extending thereacross, a drive connection 45 from said drive mechanism to said trough section, an extensible trough section having a shovel on its forward end for picking up material from the ground, and a swivel connected between said reciprocating and extensible trough sections, to 50 permit lateral swinging movement of said extensible trough section, said drive mechanism including a motor, a pair of spaced apart gears driven by said motor and mounted within said housing, said gears being mounted for rotation 55 about vertical axes, a drive connection from said gears to said reciprocating trough section, and means driven from said gears for slidably moving said loading apparatus along the ground or swinging said extensible trough section laterally including a pair of winding drums mounted on opposite sides of said trough section for rotation about parallel spaced vertical axes, a flexible feeding member adapted to be wound on each of said winding drums, friction bands for selectively holding either of said drums from rotation, a pair of spaced vertical shafts upon which said winding drums are freely mounted, geared drive connections between said shaker conveyer drive gears and the lower ends of said shafts, and clutch means selectively connecting said shafts with said drums adjacent the upper ends of said shafts, and the connection between each of said clutch means and drums including a gear coaxial with each of said shafts and adapted to be selectively driven through said clutch means, a pinion meshing with said gear and an internal gear driven by said pinion.

about vertical axes, a drive connection from said gears to said reciprocating trough section, and means driven from said gears for slidably moving said loading apparatus along the ground or swinging said extensible trough section laterally 5 including a pair of winding drums mounted on opposite sides of said trough section for rotation about parallel spaced vertical axes, a flexible feeding member adapted to be wound on each of said winding drums, friction bands for selectively 10 holding either of said drums from rotation, a pair of spaced vertical shafts upon which said winding drums are freely mounted, geared drive connections between said shaker conveyer drive gears and the lower ends of said shafts, and clutch 15 means selectively connecting said shafts with said drums adjacent the upper ends of said shafts.

2. In a material loading apparatus, a shaker conveyer drive mechanism adapted to be slidably 20 moved along the ground on its bottom and including a housing, the bottom of which forms a base for said apparatus, a conveyer trough section reciprocably mounted on said drive mechanism and extending thereacross, a drive connection 25 from said drive mechanism to said trough section, an extensible trough section having a shovel on its forward end for picking up material from the ground, and a swivel connected between said reciprocating and extensible trough sections, to 30 permit lateral swinging movement of said extensible trough section, said drive mechanism including a motor, a pair of spaced apart gears driven by said motor and mounted within said housing, said gears being mounted for rotation 35 about vertical axes, a drive connection from said gears to said reciprocating trough section, and means driven from said gears for slidably moving said loading apparatus along the ground or swinging said extensible trough section laterally 40 including a pair of winding drums mounted on opposite sides of said trough section for rotation about parallel spaced vertical axes, a flexible feeding member adapted to be wound on each of said winding drums, friction bands for selectively 45 holding either of said drums from rotation, a pair of spaced vertical shafts upon which said winding drums are freely mounted, geared drive connections between said shaker conveyer drive gears and the lower ends of said shafts, clutch 50 means selectively connecting said shafts with said drums adjacent the upper ends of said shafts, and the connection between each of said clutch means and drums including a gear coaxial with each of said shafts and adapted to be selectively driven through said clutch means, a pinion meshing with said gear and an internal gear driven by said pinion.

ROY S. BIGELOW.
